UNITED STATES PATENT OFFICE.

THOMAS HENRY WHELESS, OF NEW YORK, N. Y.

CONSTRUCTION OF VESSELS.

No. 806,222.

Specification of Letters Patent.

Patented Dec. 5, 1905.

Application filed October 14, 1903. Serial No. 177,031.

To all whom it may concern:

Be it known that I, THOMAS HENRY WHELESS, a citizen of the United States, residing at New York, in the county of New York and State of New York, have invented certain new and useful Improvements in the Construction of Vessels; and I do hereby declare the following to be a full, clear, and exact description of the invention, such as will enable others skilled in the art to which it appertains to make and use the same.

My present invention relates to improvements in small vessels adapted for high speed and having good sea-going qualities.

Boats constructed according to my invention are intended more particularly for small despatch-boats to be stationed at or near harbors and intended for use either for naval purposes or for the merchant-marine. These boats are also adapted for use as pleasure craft. The form of the hull fore and aft resembles that of a racing-scull and tapers gradually along smooth outlines to pointed ends, while the waist is deepened and sharpened in a construction similar to that of the racing-yachts of the fin-keel class. In this central portion is located the cockpit and engine-room, in which the driving mechanism is carried and also the passenger or passengers. The deep keel may be weighted, if desired, to insure further stability, and at either side of the midship-section buoyancy-chambers are provided to check the boat in rolling and to assist in preventing the boat from sinking in case of leaks.

By the foregoing construction a high speed and fine sea-going qualities are obtained. The principal weights are located near and beneath the center of buoyancy.

My invention will be understood by reference to the accompanying drawings, in which the same parts are indicated by the same letters throughout the several views.

Figure 1 is a side elevation showing one of the smaller boats constructed according to my invention. Fig. 2 is a plan view of the device shown in Fig. 1. Fig. 3 shows a section along the line 3 3 of Fig. 1 and looking in the direction of the arrows. Fig. 4 shows a section along the line 4 4 of Fig. 1 and looking in the direction of the arrows. Fig. 5 is a longitudinal vertical section through the midship portion of the boat. Fig. 5^a is a detail showing one form of reversing propellers adapted for use in the invention. Fig. 6 is a plan view of

the device shown in Fig. 5. Fig. 7 is a similar view to that shown in Fig. 5 except that the driving-engine is omitted and there is a slight change in the gear for reversing the propeller. Fig. 8 is a plan view. Fig. 9 is a longitudinal vertical section showing the stern of the boat with the rudder and yoke. Fig. 10 is a modification showing the rudder immediately in rear of the propeller. Fig. 11 is a vertical longitudinal section showing the framework of the aft part of the boat. Fig. 12 is a section along the line 12 12 of Fig. 11 and looking in the direction of the arrows. The parts shown in Figs. 11 and 12 are on a larger scale to better illustrate the details. Fig. 13 shows the framework of the midship-section of the boat. Fig. 14 shows a section along the line 14 14 of Fig. 13 and looking in the direction of the arrows. Fig. 15 shows a section along the line 15 15 of Fig. 13 and looking in the direction of the arrows.

The boat consists of three parts—the bow portion A, the waist or body portion A', and the stern portion A''. Projecting from the bottom of the waist portion is a fin-keel A³, which is preferably made of two plates of the shell of the boat, as shown at a' in Fig. 4, tapering to a point. Ballast may be inserted above the keel A³, if desired.

At either side of the waist portion of the boat some distance above the water-line I provide buoyancy-chambers A⁴, which are preferably formed of a continuous sheet of metal a⁴, connected to the side of the boat by the metal sheets a³, as shown in Figs. 3 and 4. Between these buoyancy-chambers A⁴, I provide a hatch-coaming A⁵, connected to the curved deck A⁶ of the boat by suitable ribs a⁵. This hatch-coaming is flared outward, as shown most clearly in Fig. 5, and its bottom, except the hatch a⁶, is decked over, as at A⁷, and it is provided in its after part with scuppers a⁸, (see Figs. 5 and 6,) which open outward and permit the escape of water that splashes in from above the hatch-coaming, but prevents the influx of water from the rear. Inside of this hatch-coaming I provide a hatch a⁶, which may be left open or may be partially closed by a rubber or oil-skin apron H, which is preferably drawn or gathered, as at h, (see Fig. 6,) around the waist of the occupant of the boat. Beneath this hatch I provide a seat I, having a hinged back I' and a supporting-plate I², which seat, back, and sup-

porting-plate form bulkheads, which, with the bulkhead I^3 and the side bulkheads I^4 , inclose the engine-room, and thus prevent water passing through the hatch from entering the engine-room. The seat I , back I' , and deck-plate A^7 may be removed for handling the motor.

B represents the propeller, which is preferably provided with reversing blades B' , which 10 may be mounted in any convenient way—such, for instance, as that shown in Fig. 5^a, in which the blades B' are pivoted, as at b , to the hub B^3 and are slotted to receive the pins b' , fixed on the propeller-shaft B^2 , projecting 15 from the sleeve B^4 , which sleeve is splined to slide on the propeller-shaft B^2 . This sleeve is journaled in a suitable bearing A^7 , fast to the boat.

The propeller-shaft B^2 is driven by any 20 suitable motor, preferably a hydrocarbon-motor D, having a fly-wheel D' , as shown in Fig. 5. This motor receives its supply of air through the pipe E, which extends over the gunwale and backward, which prevents 25 the washing of the water, and the products of combustion pass off through the pipe, as shown in dotted lines at E^0 .

The propeller-blades may be reversed in different ways—such, for instance, as shown 30 in Figs. 5, 5^a, and 7. In Fig. 5 the lever C, pivoted at c , carries a pin or collar engaging in the annular groove b^4 on the sleeve enclosing the propeller-shaft. This lever is moved backward or forward by means of the 35 hand-lever C^2 and the connecting-rod C' . This hand-lever is pivoted, as at c' , in front of the seat I and is provided with a suitable spring-pawl c' , engaging in the rack C^3 . It will be seen that by moving this lever C^2 40 backward or forward the sleeve B^4 will be moved longitudinally on the propeller-shaft B^2 , thus swinging the propeller-blades about the pivots b and reversing same when desired. In the reversing mechanism shown in Fig. 7 45 the collar c^4 is connected to the arms C^4 on a shaft C^6 , which shaft carries the crank C^6 , connected by the rod C^7 with the crank C^8 on the shaft C^9 , which shaft is turned by means of the handle C^{10} . This construction is necessary 50 if the rubber apron H be used, so that the operator has all means for regulating and steering conveniently at hand. Any other suitable means for reversing the propeller-blades may be adopted, if desired.

55 The inner framework of the boat comprises not only the seat I and the bulkheads I , I' , I^2 , I^3 , and I^4 , already referred to, but also the bulkheads K and K' and suitable frames K^2 , made of angle-irons and fore-and-aft girders, 60 comprising the inner keel M, made preferably in the form of a T-iron, and the angle-beams M' , above which the deck A^6 is mounted. The details of this framework are shown in Figs. 11 to 15. Instead of having the frames open, 65 as shown at Figs. 12 and 14, some or all of

these frames may be made in the form of bulkheads, as indicated in Fig. 15 and as shown at K and K' in Figs. 5 and 7, some of which may be used to inclose chambers for fuel-tanks, if desired.

The two sides of the boat are preferably made of plates which terminate at the top at each side of the deck, as shown in Fig. 12, and at the bottom in the keel, and also the deck can be made of a curved plate or a thin waterproof sheet and covered with wooden planks. These plates are secured to the frames and also to the fore-and-aft beams or girders, including the keel, and thus a structure of sufficient rigidity is secured.

To steer the boat, a suitable rudder is provided, with mechanism for controlling the same. In Fig. 10 the rudder P is shown as connected to the stern-post Q in the usual way and is driven by a suitable tiller-rope 85 (not shown) connected to the steering-wheel P^3 . In the form of device shown in Figs. 7, 8, and 9 the rudder is pivoted in the after portion of the boat, as to the skeg A^8 , and the rudder-head P^6 carries a yoke P' , to which the tiller-ropes P^2 are connected. This yoke is mounted beneath a waterproof casing p , and the ropes P^2 are rove through pipes p' , so that the water will not wash into the boat through the opening at the rudder-head. 95 These ropes P^3 are led forward to the steering-wheel P^4 , on which they are wound in the usual way.

Heretofore it has been considered desirable to make the maximum depth of the hold of boats below the normal water-line less than the maximum width of the beam. In fact, it has been considered desirable in order to increase the speed to have the depth of the hold below the water-line as small as possible and to lessen the draft of the boat in order to secure as much of a skimming action on the water as possible. To secure the necessary stability, weighted keels have been resorted to. I have found by reversing this procedure and making the bottom line of the hull of the boat extend obliquely upward fore and aft into the bow and stern portions I can not only secure a better speed, but at the same time can secure adequate stability. Therefore I make 100 my boat with long and narrow bow and stern portions and a depth inside the skin of the boat at the waist below the normal water-line greater than the maximum width of the beam 105 at the waist, with the bottom line of the hull extending in an upward direction toward the bow and stern from the waist portion of the boat. By the "bottom line of the hull of the boat" I mean to exclude any downward projection, such as a fin-keel or bulb-keel or the like. By "maximum breadth of beam" I refer to the beam of the hull proper of the boat 110 exclusive of the buoyancy-chambers or overhang.

My invention is primarily intended to re- 115

late to boats of considerable length and narrow beam. In practice the beam would not exceed ten feet; but the length might be widely varied, according to conditions required of each type of boat.

By having the hull very deep in the waist it is possible to make the propeller-shaft horizontal and at the same time to immerse the propeller at a satisfactory depth below the surface of the water. The advantage of having the propeller-shaft horizontal is to have a straight thrust, while the advantage of having the propeller at a considerable depth is that it acts on the water under pressure and diminishes the slip.

It will be noted that the weights in the boat are mainly located below the center of buoyancy, so that the boat will be stable in a seaway, while the buoyancy-chambers A⁴ will prevent it from rolling too far or from capsizing.

Thus it will be seen that I provide a boat having fine lines, which may be rapidly propelled through the water with the expenditure of comparatively small amount of power, and which is safe and seaworthy.

While I have shown a small boat provided with a hydrocarbon-engine, other engines may be used, or the boat may be propelled by hand or foot power. Moreover, it will be evident that the size of the boat may be varied to suit varying requirements. It will be obvious that these and various other modifications might be made in the herein-described vessel which could be used without departing from the spirit of my invention.

Having thus described my invention, what I claim, and desire to secure by Letters Patent of the United States, is—

1. A marine vessel comprising long shallow bow and stern portions, and a deep and narrow waist portion, provided with a hatch, a deep fin-keel projecting from said waist, and a hatch-coaming mounted above said waist portion, substantially as described.

2. A marine vessel comprising long shallow bow and stern portions, and a deep and narrow waist portion, provided with a hatch, a deep fin-keel projecting from said waist, a hatch-coaming mounted above said waist portion, and mechanism for propelling the boat mounted in said waist portion, substantially as described.

3. A marine vessel comprising long shallow bow and stern portions, and a deep and narrow waist portion, provided with a hatch, a deep fin-keel projecting from said waist portion, a hatch-coaming mounted above said waist, with a propeller mounted in rear of said waist, and a driving-engine mounted in said waist, substantially as described.

4. A marine vessel comprising long shallow bow and stern portions, and a deep and narrow waist portion, with a deep fin-keel projecting from said waist, a hatch in the deck above said

waist, a hatch-coaming surrounding said hatch, a propeller mounted in rear of said waist, and a hydrocarbon-engine mounted in the lower part of said waist for driving said propeller, substantially as described.

5. A marine vessel comprising long shallow bow and stern portions, and a deep and narrow waist portion, provided with a hatch, a deep fin-keel projecting from said waist, a hatch-coaming mounted above said waist, an adjustable hood mounted over said hatch, a seat mounted below said hatch provided with a water-tight back, the said seat and back forming parts of a water-tight bulkhead, and an engine-room in rear of said bulkhead, and mechanism for propelling the boat mounted in said engine-room, substantially as described.

6. A marine vessel comprising long shallow bow and stern portions, and a deep and narrow waist portion, provided with a hatch, a deep fin-keel projecting from said waist portion, a hatch-coaming mounted above said waist, a seat mounted below said hatch provided with a water-tight back, the said seat and back forming parts of a water-tight bulkhead, and an engine-room in rear of said bulkhead, a propeller mounted in rear of said waist, and a driving-engine mounted in said engine-room, substantially as described.

7. A marine vessel comprising a long shallow bow portion and a long shallow stern portion with deep and narrow waist, the bottom lines connecting said waist and said bow and stern portions being curved forward and aft respectively, with buoyancy-chambers at each side of said waist, and a keel projecting downward from said waist, substantially as described.

8. A marine vessel comprising a long shallow bow portion converging downwardly in its vertical transverse contour-lines, and a long shallow stern portion, with a deep and narrow waist, and a keel beneath said waist, the transverse contour-lines of the waist converging to the keel, and the keel extending upward, forward and aft respectively, and merging into the bow and stern portions, substantially as described.

9. A marine vessel comprising a long shallow bow portion converging downwardly in its vertical transverse contour-lines, and a long shallow stern portion, with a deep and narrow waist, and a keel beneath said waist, the transverse contour-lines of the waist converging to the keel, and the keel extending upward, forward and aft respectively, and merging into the bow and stern portions, and the lower portion of said waist being weighted, substantially as described.

10. A marine vessel comprising a long shallow bow portion converging downwardly in its vertical transverse contour-lines, and a long shallow stern portion, with a deep and narrow waist, and a keel beneath said waist, the trans-

verse contour-lines of the waist converging to the keel, and the keel extending upward, forward and aft respectively, and merging into the bow and stern portions, and the lower 5 portion of said waist being weighted, with buoyancy-chambers at each side of said waist, substantially as described.

11. A marine vessel comprising a long narrow bow portion, and a long shallow stern 10 portion, with a deep and narrow waist, the draft of which to the bottom of the hull proper exceeds the maximum beam of said waist at the water-line, substantially as described.

12. A marine vessel, comprising a long narrow bow portion, and a long shallow stern 15 portion, with a deep and narrow waist, the draft of which to the bottom of the hull proper exceeds the maximum beam of said waist at the water-line, the bottom line of which vessel 20 extends obliquely upward fore and aft into the said bow and stern portions, and the lower portion of said waist being weighted, substantially as described.

13. A marine vessel comprising a long narrow bow portion and a long shallow stern 25 portion with a deep and narrow waist, the draft of which to the bottom of the hull proper exceeds the maximum beam of said waist at the water-line, and mechanism for propelling

the boat mounted low down in said waist, 30 substantially as described.

14. A marine vessel comprising a long narrow bow portion and a long shallow stern portion with a deep and narrow waist, the draft of which to the bottom of the hull proper 35 exceeds the maximum beam of said waist at the water-line, the bottom lines connecting said waist, and said bow and stern portions being curved forward and aft respectively, and a weighted keel projecting downward 40 from said waist, substantially as described.

15. A marine vessel comprising a long narrow bow portion and a long shallow stern portion with a deep and narrow waist, the draft of which to the bottom of the hull proper 45 exceeds the maximum beam of said waist at the water-line, the bottom lines connecting said waist, and said bow and stern portions being curved forward and aft respectively, with buoyancy-chambers at each side of said 50 waist, substantially as described.

In testimony whereof I affix my signature in presence of two witnesses.

THOMAS HENRY WHELESS.
